UNITED STATES PATENT OFFICE.

FRANK R. PERRY, OF CHICAGO, ILLINOIS, ASSIGNOR, BY MESNE ASSIGNMENTS, OF ONE-HALF TO BENJAMIN MOTOR PRODUCTS CO., OF DETROIT, MICHIGAN, A CORPORATION OF DELAWARE.

DUPLEX CARBURETOR.

1,426,335.

Specification of Letters Patent. Patented Aug. 15, 1922.

Application filed January 7, 1918. Serial No. 210,691.

To all whom it may concern:

Be it known that I, FRANK R. PERRY, a citizen of the United States, residing at Chicago, in the county of Cook and State of Illinois, have invented certain new and useful Improvements in Duplex Carburetors, of which the following is a description.

My invention belongs to that general class of devices known as carburetors and relates particularly to a carburetor for use on internal combustion engines for carbureting or co-mixing a suitable hydro-carbon and air to produce a suitable mixture for the efficient running of the engine. The invention particularly relates to a carburetor applicable for the co-mixing of one or more hydro-carbons and air, either singly or independently as may be desired, or a combined mixing of a plurality of hydro-carbons and air at the same time. The invention has among its objects a production of the kind described that is simple, efficient, compact, durable, and satisfactory for use wherever found applicable. It has particularly as an object the production of a carburetor for carbureting or vaporizing and mixing with air the heavier hydro-carbons such as kerosene, distillate, and the like, as well as the lighter hydro-carbons such as gasoline. With my improved device the engine may run on the heavier hydro-carbon alone or on the lighter hydro-carbon alone, or both may be employed at the same time. Another object is the production of a device that will cause a more complete breaking up of the hydro-carbon so that there will be no unvaporized particles which may escape past the piston rings into the crank case. Among its further objects is the production of a device that may be so regulated and controlled that the engine will not run hot or over heat even in the warmest or hottest weather and yet it will operate efficiently in the coldest weather. Many other objects and advantages of the construction herein shown and described will be obvious to those skilled in the art from the disclosure herein made.

To this end my invention consists in the novel construction, arrangement and combination of parts herein shown and described and more particularly pointed out in the claim.

In the drawings, wherein like reference

characters indicate like or corresponding parts,

Figure 1 is a view in elevation of my improved carburetor applied to a well-known type of engine, the engine being shown in dotted lines forming no part of the present invention, however;

Figure 2 is a sectional view taken on line 2-2 of Figure 3;

Figure 3 is a vertical sectional view through my preferred form of carburetor;

Figure 4 is a sectional view taken substantially on line 4-4 of Figure 3;

Figure 5 is a detail view in section illustrating a changed position of the valve 50;

Figure 6 is a sectional view taken substantially on line 6-6 of Figure 7 illustrating the heat control valve; and

Figure 7 is a sectional view taken substantially on line 7-7 of Figure 6.

It may be mentioned that in the installation of the device it is immaterial on which side of the engine the carburetor is placed or which way the device is turned, the same being installed to fit the particular engine upon which it is to be used and of proper size and form. In Figure 1 the device is shown installed on a Ford type engine in which 1 represents the engine, 2 a portion of the intake manifold and 3 a portion of the exhaust manifold. The device illustrated is intended particularly for the carbureting of kerosene, distillate or the like, as well as gasoline or its equivalent, so that the engine may be started on gasoline or the like and then continue to run on gasoline or kerosene, or both.

Referring particularly to Figures 1, 3 and 4, a suitable casing or tubular pipe 4 is connected by means of an elbow 5 or its equivalent with the intake manifold 2. The opposite end of the casing is provided with an air intake 6 at which may be arranged a valve 7. The valve 7 is shown arranged on a guiding stem 8, and provided with a control spring 9. The valve may be adjusted by turning the head 11 to screw the same in or out and is normally locked in the desired position by the locking member 10 as illustrated in Fig. 3 of the drawings. I also preferably provide a choke valve 14 in the casing 4 which is shown mounted on a shaft 15 extended to the exterior of the casing.

At the outlet 16 I provide a butterfly valve 17 which may be mounted on the shaft 18 and which is also controlled from the exterior of the casing. A Venturi collar or tube 19, however, is arranged as shown, the purpose of this being explained more fully hereafter. As shown in Figure 1, I provide an arm 20 on shaft 15 by means of which the valve 14 may be controlled. For convenience 10 a rod 21 is provided for operating the arm 20, the rod extending to a convenient point, as for example, when the device is on an automobile, to the dash or steering wheel or some point convenient to the driver. The 15 arm 22 is also connected by suitable means as, for example, a rod (not shown) to a point convenient for operation as, for example, the throttle lever on the steering wheel or to the accelerator, or both.

20 Arranged adjacent the casing 4 is a heater casing or shell 24 provided with an inlet 25 and outlet 26, this casing being arranged for the passage of a heating medium as, for example, the exhaust gases from the engine 25 through the same. I have shown the casing 24 connected by a suitable piping 27-28 with the exhaust manifold 3, the same, however, being preferably constructed as at 29 or in an equivalent manner to provide a 30 valve chamber or casing. The piping 27-28 is connected with the pipe 30 which opens into the pipe parts 32 and 33. The part 32 is connected to an elbow 31 or its equivalent so that it is in communication with the outlet 26 of the casing 24 and the pipe 33 is connected with the muffler or to the open, the piping constituting a loop of which the heater is a part, the heating medium being conducted through the loop as desired.

35 40 Arranged in the valve casing 29 is a valve 34, the same being mounted on a stem 35 or its equivalent, which is shown provided with an arm 36 arranged to be actuated by a rod 37 or its equivalent preferably extending to the dash or some convenient point for the operator to manipulate the same. When the valve is in the position shown in Figures 3 and 6 the exhaust gases obviously will pass through the part 27, casing 24 and out 45 through the elbow 31 and part 32 into the exhaust pipe 33. When the valve, however, is swung to the position indicated by the dotted lines in Figure 6 the exhaust gases will pass directly from pipe or part 28 into 50 pipe 30 and to the exhaust pipe 33. Some, however, may back up through pipe 32 to the interior of the heater. The heater and piping as mentioned form substantially a loop in the pipe through which the heated 55 gases may be passed or not as desired. Obviously, if the valve 34 is moved so as to leave both the opening through pipe 30 and through pipe 27 open, the amount of heat passing through the loop will be diminished, 60 and yet some heat will pass through the 65 loop. By manipulating the valve as desired or found necessary, the amount of heat may be controlled at all times for cold or warm weather, or different hydro-carbons.

70 Arranged in the heater casing 24 is a pan-shaped fuel container or receptacle 39, the same serving as a closure for the casing part 24. Part 39 is provided with a closure 40. Arranged within the container 39 is a series of baffles 41 of the desired size and shape. 75 These are preferably so arranged, however, that the hydro-carbon passing through the container may come in contact with the bottom of the container and be thoroughly mixed and vaporized and partially carbureted. If desired balls 53 of suitable material or their equivalents may be used as additional baffles. The container is provided with an inlet at 43 to which extends a feed pipe 42, the same being preferably 80 disposed at one end of the container. The same is also provided with an outlet 44, preferably at the opposite end, communicating with the pipe 45 extending as at 47 to the interior of the casing 4. As shown, 85 it extends into or adjacent the Venturi tube or collar 19. The pipe 45 is shown secured to the part 39 and secured to the part 4 by means of the threaded members 46, it being understood that any equivalent construction 90 may be employed. The part 39 may also be provided with an inlet 48 to which extends a feed pipe 49, the inlet 48 in the preferred construction being adjacent the outlet 44, as most clearly shown in Figure 3. 95

100 Arranged at the outlet or discharge port 44 is a valve 50 which may be provided with an operating arm 51 and control rod 52 extending to a convenient point, as for example, the driver's seat, or to the dash or steering wheel.

105 I prefer to employ a three-way valve 50, which may be constructed as shown or in an equivalent manner, so that the same may be turned substantially as shown in Figure 3 110 or Figure 5 or turned to a position where the outlet 44 is connected as shown in Figure 3, and at the same time pipe 49 is open to pipe 44. This is possible by turning valve 50 to the reverse position to that shown in 115 Figure 5. However, in this connection it will be noted that the relative size of the two inlets to the valve may be varied by varying the adjustment of the valve.

120 It will be noted by referring to Figure 3 that the pipes 42 and 49 extend some distance below the casing 24 and carry a plate or member 55 which is spaced from the casing 24 by the spacing members 56. The plate 55 forms a top or cover for the two 125 shells or casings 57 and 58, which provide float chambers, the shells being secured in place by the nuts 59 and 60 or equivalent means. In this connection it may be mentioned that the pipes 52 and 59 are open at 130

the bottom so as to permit the admission of a limited amount of air. The pipe 42 is provided with a branch pipe 61 extending to substantially adjacent the bottom of the 5 chamber in shell 57. The shell 57 is provided with an intake port 62, passage of fluid to the shell being normally controlled by a valve 63 carried by the float 64 which may be hinged at 65. The pipe 49 is provided with a similar branch pipe 66 in shell 58 and an intake port 67 is arranged as shown in the plate 55, 68 being the valve and 69 its float hinged at 70.

As most clearly shown in Figure 1, port 15 62 is connected with the feed pipe 71 and port 67 with the feed pipe 72, these pipes being connected in turn to suitable tanks or receptacles containing the hydro-carbons. I prefer to connect feed pipe 71 to a tank 20 containing the kerosene, distillate or heavy hydro-carbon and pipe 72 to a tank or receptacle containing a lighter hydro-carbon such as gasoline or the like. I have not considered it necessary to illustrate the 25 tanks, as they may be of any approved construction, but it may be mentioned ordinarily the first mentioned tank is of greater capacity than the last mentioned, as the heavier hydro-carbon ordinarily used for 30 the greater part of the running of the engine and the lighter hydro-carbon in starting, warming up, or at such other times as may be desired.

The operation of the carburetor may be 35 briefly described as follows: Assuming that the same is connected up as shown in Figure 1, or in an equivalent manner, and that the engine is not running and cold. In this case valve 50 is turned as shown in Figure 5 and 40 the engine started either by self-starter or by crank or the like. The lighter hydro-carbon from the float chamber in shell 58 is free to enter pipe 47 and as the engine turns over it draws air and hydro-carbon through 45 pipe 49, the gasoline in shell 58 being drawn up through pipe 66 and with the air passes through or past valve 50, through pipe 47 and mixing with the air in part 4, past the butterfly valve 17 and through the outlet 16 50 and intermediate piping to the engine cylinder. If desired the choke valve 14 may be closed to the desired extent in starting. As soon as the engine starts to fire, assume that the valve 34 is in the position shown in 55 Figure 3, the exhaust gases pass through the casing 24, out through 31—32, to the exhaust pipe 33. The first firing, however, heats the charge passing through pipe 49 as well as in the container 39. As soon as the container 39 is sufficiently warmed up the valve 50 may be turned as shown in Figure 3 or to the position where both pipe 49 and the interior of the casing is open to pipe 47. At 60 this time air is drawn through pipe 42 and 65 the fuel or hydro-carbon such as kerosene in

shell 57 is drawn through pipe 61 through pipe 42 into the container 39. It is not only vaporized to a certain extent as it passes through the pipe 42 in the path of the ingoing exhaust gases but as soon as it reaches 70 the container 39 is thoroughly and completely heated and vaporized and passes into pipe 47 from which it is discharged into the path of the ingoing air through the part 4 admitted through the inlet 6. At such time 75 as the engine becomes sufficiently heated to return the kerosene or heavier hydro-carbon alone, the valve 50 may be turned as shown in Figure 3 entirely cutting off the gasoline or lighter hydro-carbon. It will be noted 80 that the inlet 6 for the admission of air is close to the part 27 and consequently the air is to some extent heated before entering part 4. However, I have found that it is not desirable to heat the air passing through 85 part 4 to any considerable extent, as a more efficient mixture is obtained by mixing the cooler air with the vaporized hydro-carbon and at the same time the mixture is not as hot when discharged into the engine, consequently 90 the over-heating of the engine is ordinarily entirely prevented.

If at any time it is desired to reduce the heating of the hydro-carbon valve 34 may be manipulated to regulate the amount of 95 heated gases passing through the casing 24. In the summer time it is possible that there will be occasions when the valve 34 may be entirely shut after the engine has been thoroughly heated up. Where the exhaust 100 gases are passed through the loop some of the air entering through pipes 42 and 49 would be partially heated by the part 32, as will be obvious by referring to Figures 3 and 4, from which it will be seen that the 105 inlet end of the pipes are substantially adjacent the pipe 32.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned, 110 except as set forth in the appended claim.

What I claim as new and desire to secure by Letters Patent is:

In a device of the kind described, a supply chamber to contain a heavy fuel, a supply chamber to contain a lighter fuel, means for producing a primary mixture of each of said fuels with a small quantity of air, a conduit for a heating medium arranged adjacent said supply chamber, a chamber providing an extended surface mounted in said conduit, an outlet connection from the supply chamber for the heavy fuel across said conduit to the inlet end of the heating chamber, an outlet connection from the supply 120 125 130

chamber for the lighter fuel across said conduit to the outlet end of said chamber, a valve at said outlet to control the flow of mixture from the heating chamber or the 5 light fuel supply chamber to the nozzle of a mixer, and means for supplying additional air to said mixer.

In testimony whereof, I have hereunto signed my name in the presence of two subscribing witnesses.

FRANK R. PERRY.
